UNITED STATES PATENT OFFICE.

JACOB STRAUS, OF ST. LOUIS, MISSOURI.

SWEAT-PAD FOR HORSE-COLLARS.

SPECIFICATION forming part of Letters Patent No. 313,963, dated March 17, 1885.

Application filed November 19, 1884. (No model.)

To all whom it may concern:

Be it known that I, JACOB STRAUS, of the city of St. Louis, in the State of Missouri, have invented a certain new and useful Improvement in Sweat-Pads for Horse-Collars, of which the following is a full, clear, and exact description, reference being had to the accompanying drawings, forming part of this specification, and in which—

10 Figure 1 is a perspective view of my improved sweat-pad. Fig. 2 is a side view. Fig. 3 is a transverse section taken on line 3 3, Fig. 2. Figs. 4 and 5 are diagrams illustrating the manner of making my improved pad. Fig. 6 is a modification.

15 My invention relates to an improved pad; and it consists in features of novelty herein-after fully described, and pointed out in the claims.

20 Referring to the drawings, A represents the pad, which may be provided with loops B, to receive the collar-straps, and straps C, to go around the hames, to hold the pad in place under the collar. The straps I have shown 25 are made fast by one end to the pad, and are slotted at the free ends, as shown at D, to receive buttons D'; but any other suitable form of straps and fastenings may be used.

25 In making the pad the face and back are 30 stitched together by a seam, I, extending all the way around. (See Fig. 4.) The next thing to be done is to make one or more slits or cuts, J, in the back, preferably one near each end, as shown, and then the article is 35 turned inside out through means of the openings J, thus hiding the edge formed by the seam I, as shown in Fig. 5. The article is then quilted by a number of seams, L, thus forming pockets, as shown in Fig. 3, which 40 are stuffed with hair or other suitable material, M, that is inserted through the openings J.

45 I prefer to mix ground or pulverized alum, salt, or other healing material with the stuffing before putting it into the pad, which is drawn out by the heat and dampness of the animal's shoulders and acts to harden or tan the skin of the shoulders and to heal any galls or sore places on the horse's shoulders. The hair could be saturated in alum-water.

50 My improved pad has a number of advan-

tages over the old forms of sweat-pads, among which are, first, the cheapness of its manufacture. As the seams are all made before stuffing, every stitch can be done by machine, thus avoiding the slow, expensive, and tedious 55 method of doing it by hand, or "tufting," as it is called in the trade; second, the stuffing being done after the seams are all made, the hair or other material is not caught by the stitches, and therefore a much more elastic 60 and uniform pad is produced; third, the stuffing not being caught by the stitches, it can be moved or taken out from any desired point by an instrument inserted through the slots J, so as to form a depression in the pad opposite any sore place there may be on the animal's shoulders; fourth, the alum or its equivalent mixed with the stuffing acts to heal and tan the animal's shoulders, as above mentioned; fifth, the pad, being turned after the 70 outer seam, I, is made all around the outer edge or periphery of the pad, has a smooth finished appearance, no rough edge projecting.

Another form of fastening is shown in Fig. 6, where the strap C passes twice through a 75 leather button. The strap fits down on the collar under the hame, and is held there by the button, which cannot be pulled between the hame and collar. The button can be adjusted on the strap to suit.

80 I reserve the right to claim in a subsequent application the stuffing of hair or other suitable material with which alum or its equivalent is mixed.

I claim as my invention—

85 1. A sweat-pad for horse-collars, stitched all the way around before being turned, and having pockets to receive stuffing, which are formed by rows of stitches that do not pass through the stuffing of the pad, for the purpose specified.

2. A sweat-pad for horse-collars, having pockets and transverse slits, the pockets being formed by rows of stitches that do not pass through the stuffing of the pad, substantially 9 as and for the purpose set forth.

JACOB STRAUS.

In presence of—

GEO. H. KNIGHT,

SAML. KNIGHT.
